UNITED STATES PATENT OFFICE.

THOMAS I. RANKIN, OF PHILADELPHIA, PENNSYLVANIA, ASSIGNEE TO
ABRAM COX STOVE COMPANY, OF PHILADELPHIA, PENNSYLVANIA,
A CORPORATION OF PENNSYLVANIA.

DESIGN FOR A HEATING-STOVE.

SPECIFICATION forming part of Design No. 35,460, dated December 17, 1901.

Application filed September 5, 1901. Serial No. 74,467. Term of patent 7 years.

To all whom it may concern:

Be it known that I, THOMAS I. RANKIN, a citizen of the United States, residing in Philadelphia, Pennsylvania, have invented and produced a certain new and original Design for a Heating-Stove, of which the following is a specification.

My design for a heating-stove is clearly illustrated in the accompanying drawing, which 10 represents the stove in perspective.

The essential features of the design are the ornamental skirt which surrounds the fire-chamber of the stove and the ornamentation of the fire-door.

15 G is the base of the stove, on which is mounted the fire-pot G², and above the fire-pot is the body-section G', surmounted by a cap G³.

Extending from the lower portion of the body-section G' of the stove is a deep skirt 20 G⁴. This skirt extends down over the fire-pot, as shown in the drawing. The skirt is ornamented by a number of open-work scrolls divided into sections.

The fire-door g has a name-plate g' near the upper end. Directly below the name-plate 25 are three openings g², and below the openings is a small medallion g³, and on the fire-door is scroll-work ornamentation in keeping with the ornamentation of the rest of the stove.

The cap G³ of the stove is ornamented in 30 keeping with the general design of the ornamentation of the stove.

I claim—

The design for a heating-stove as herein described, and as illustrated in the accompanying drawing. 35

In testimony whereof I have signed my name to this specification in the presence of two subscribing witnesses.

THOMAS I. RANKIN.
